UNITED STATES PATENT OFFICE.

CHARLES T. BURLIN, OF WHITINSVILLE, MASSACHUSETTS, ASSIGNOR TO WHITIN MACHINE WORKS, A CORPORATION OF MASSACHUSETTS.

METHOD OF MAKING FLIERS.

1,042,645.

Specification of Letters Patent.

Patented Oct. 29, 1912.

Application filed July 13, 1911. Serial No. 638,295.

To all whom it may concern:

Be it known that I, CHARLES T. BURLIN, a citizen of the United States, residing at Whitinsville, in the county of Worcester and State of Massachusetts, have invented a new and useful Method of Making Fliers, of which the following is a specification.

This invention relates to a method of making fliers.

10 Fliers, as usually made, are formed of a piece of flat stock, to which are welded a pair of cylindrical bearing members projecting in opposite directions from the flat sides of the shank. This member is then shaped up in dies by drop forging generally, and the ends drawn out and otherwise operated upon to form the complete flier. Fliers made in this way have been quite expensive, not only on account of the time consumed in the welding operation, but also on account of the waste due to imperfect welding which aggregates a large percentage of the total number of blanks formed.

Many attempts have been made to form 25 the two cylindrical parts constituting the bearings of the flier integral with the rest of the frame but, so far as I am aware, these attempts have always involved successive and repeated operations on the blank in 30 dies to draw out these projections in the direction of pressure, and have not produced a satisfactory or practical method of accomplishing the desired result.

The principal object of this invention is 35 to provide a practical and efficient method of forming the whole flier of a single integral piece of stock without repeatedly transferring the blank back and forth between the dies.

40 Reference is to be had to the accompanying drawings in which—

Figure 1 is a plan of the blank after the first drop forging operation. Fig. 2 is a plan of the same blank after the second operation showing the projections cut off to length. Fig. 3 is a plan of the blank after the third operation. Fig. 4 is a side elevation of the blank as shown in Fig. 3. Fig. 5 is an elevation of the flier formed by this 50 method, and Fig. 6 is a plan of the preliminary shaping die used.

The invention preferably is carried out by taking a blank, preferably a piece of bar metal of cylindrical form, and shaping it up in a single pair of dies so as to form a

pair of ends q and q' both of substantially cylindrical form, one of them tapering at a^2 to form an enlarged section near the center of the blank and having a circular disk-shaped enlargement a^3 at the large end of 60 this tapering portion. This is accomplished by placing the original blank in a die 10 having a conformation like the blank shown in Fig. 1 and just described and bringing down on it a second die of the same shape, 65 a plurality of times, preferably turning the blank between each two successive operations. This disk shaped enlargement is very important as it is the only means I have discovered by which the next step can 70 be performed quickly, accurately, and practically so as to secure the desired result, without the loss of time due to repeatedly changing the blank from one die to another and back. After this blank has been formed 75 it is taken out of this die and placed in a second die 11 and operated on by a similar die. These dies are formed to produce the blank shown in Fig. 2. This blank is pro- 80 vided with two cylindrical ends b and b' made from the portions a and a' . The die does not greatly alter these portions but it somewhat draws them out so as to elongate them and smooths them up. The portion b has a tapering part b^2 which terminates at a base b^3 and then is drawn out smaller at b^4 . The disk shaped part a^3 is formed out at this stamping into two opposite projections b^5 and b^6 , both of cylindrical form, and in axial alinement. One is 85 made longer than the other either in the dies or by cutting off their ends after the blank is removed. It will be seen therefore that these opposite projections are formed from a single integral piece of stock by drawing 90 them out transversely to the direction of pressure, that each of the operations so far described is performed in a single pair of dies by repeated blows, and that after one pair of dies has been used, and the blank 95 removed, the blank never has to be transferred back to it. These projections constitute a transverse cylinder for the formation 100 of the bearing. A small projection b^7 also is formed to furnish some additional metal. This blank having been formed, it is put into one of the dies ordinarily employed for the blank which is usually manufactured by welding and formed up into the shape 105 shown in Figs. 3 and 4. In this case a flat 110

tapering end c is provided and a cylindrical end c' on the other side having a flattened shank c^2 . The end c has wings c^3 , as usual, and the parts b^5 and b^6 are formed into 5 smaller and smoother cylindrical projections c^5 and c^6 . This blank need not be described in detail as it is well known in this art except that as heretofore made, the parts c^5 and c^6 are usually welded to the main body 10 before it is shaped up into this form, whereas, according to this process they are integral with it thus eliminating practically all the waste due to imperfect welding. It will be understood, of course, that after 15 this blank c is formed the flier d shown in Fig. 5 is formed up by the usual process, no change being necessary in these operations. This is another advantage of my method, as the old dies used through the steps from 20 the shape shown in Fig. 3 to that shown in Fig. 5 can be employed without change.

It will be understood, of course that the ends of the cylindrical portions b and b^5 25 are cut off to the proper length between the operations represented by Figs. 2 and 3. The projection b^6 also can be cut off if desired and the end of the shank c' by which it is handled is cut off to the proper length at a later stage in the process.

30 While I have illustrated and described a specific embodiment of the invention, I am aware that many modifications can be made therein without departing from the scope of the invention as expressed in the claims. 35 Therefore, I do not wish to be limited to all the details of construction herein shown and described, but

What I do claim is:—

1. The method of forming a flier, which consists in forming from a blank a long body provided with an integral substantially circular disk at a point near the center thereof, then working said blank by drop forging to form a second shape having cylindrical ends and an integral transverse 45 cylindrical member near the center, drop forging this latter blank to reduce the thickness of one cylindrical end and to form wings thereon, thus providing a substantially flat member on one end and flattening 50 the shank on the other end near the transverse member, and finally forging this blank and drawing it out to form the flier.

2. The method of forming a flier which consists in forming from a blank a long substantially cylindrical body, forming thereon an integral transverse substantially cylindrical member near the center, drop forging this blank to reduce the thickness of one end of the long body to form opposite wings thereon to provide a substantially flat member on one side of the transverse cylindrical member and flattening the shank of the other end near the transverse member, and finally forging this blank and 60 drawing out both ends to form the flier.

In testimony whereof I have hereunto set my hand, in the presence of two subscribing witnesses.

CHARLES T. BURLIN.
